UNITED STATES PATENT OFFICE

147,546

DESIGN FOR A WRIST WATCH CASE

Andrew Gates, New York, N. Y.

Application August 22, 1946, Serial No. 132,738

Term of patent 7 years

(Cl. D42—8)

To all whom it may concern:

Be it known that I, Andrew Gates, a citizen of the United States and residing in New York city, New York, have invented a new, original, and ornamental Design for a Wrist Watch Case, of which the following is a specification, reference being had to the accompanying drawing, forming part thereof.

Figure 1 is a top plan view of a wrist watch case showing my new design;

Figure 2 is a side elevational view of the same.

I claim:

The ornamental design for a wrist watch case, as shown.

ANDREW GATES.
